UNITED STATES PATENT OFFICE.

ALOIS A. RITTER, OF RACINE, WISCONSIN, ASSIGNOR TO HARTMAN TRUNK COMPANY, OF RACINE, WISCONSIN, A CORPORATION OF WISCONSIN.

DESIGN FOR A LOCK FOR WARDROBE TRUNKS.

Application filed November 28, 1924. Serial No. 11,519. Term of patent 7 years.

To all whom it may concern:

Be it known that I, ALOIS A. RITTER, a citizen of the United States, residing at Racine, in the county of Racine and State of Wisconsin, have invented a new, original, and ornamental Design for Locks for Wardrobe Trunks, of which the following is a description, reference being had to the accompanying drawing, forming part thereof.

In the drawing Fig. 1 is a front view of the trunk lock showing my new design; and Fig. 2 is an edge view thereof.

I claim:

The ornamental design for a lock for wardrobe trunks as shown.

ALOIS A. RITTER.
